DESIGN FOR A LAMP.

Application filed June 13, 1923. Serial No. 6,479. Term of patent 7 years.

To all whom it may concern:

Be it known that I, FREDERICK ROETTGES, a citizen of the German Republic, and resident of Stamford, in the county of Fairfield and State of Connecticut, have invented a new, original, and ornamental Design for Lamp, of which the following is a specification, reference being had to the accompanying drawing, forming part thereof.

Fig. 1 is a front view of a lamp, showing my new design.

Fig. 2 is a plan view of the top of the lamp, a part of the surface ornamentation being shown, it being apparent that the re-

mainder of the surface ornamentation is a repetition of the same design.

Fig. 3 is a plan view of the base of my lamp taken on line 3—3 of Figure 1 and looking in the direction of the arrows, a part of the surface ornamentation being shown, it being apparent that the surface ornamentation on the remainder of the base is a repetition of the same design.

I claim:

The ornamental design for a lamp, as

FREDERICK ROETTGES.
